UNITED STATES PATENT OFFICE

FREDERICK HENRY, OF SOUTH BEND, INDIANA, ASSIGNOR TO THE STUDEBAKER CORPORATION, OF SOUTH BEND, INDIANA, A CORPORATION OF NEW JERSEY

GLASS BINDING TOOL

Application filed September 18, 1931. Serial No. 563,543.

This invention relates to a tool for applying a binding strip to the edge of a panel and more particularly to a tool for applying a channel shaped rubber binding strip to the edge of a glass window panel for an automobile body, and has for its principal object the provision of a tool by means of which the binding strip may be quickly and firmly secured upon the edge of the panel and which 5 at the same time will protect the hands of the operator from injury due to contact with sharp portions of the panel edge.

It is a further object to provide a tool of the character described that is light in weight 15 and so formed as to fit comfortably into the hands of the operator so that it will not produce discomfort or undue fatigue.

It is also an object of the invention to provide a device of the character described 20 that is simple in construction, easy and economical to manufacture, and which will not readily get out of order in use.

Other objects and advantages will appear 25 as the description proceeds.

In the accompanying drawings, there is illustrated one mechanical embodiment of the device of the invention per se, and also an embodiment showing a strip cutting and stapling device attached to the tool. The 30 drawings, however, are to be taken as illustrative only and the scope of the invention is to be limited solely by the scope of the subjoined claims.

In the drawings:

Figure 1 illustrates a suitable example of 35 the application of the device of the invention.

Figure 2 is a top plan view of the tool which forms the subject matter of this invention.

Figure 3 is an elevational view of the device of the invention, a portion being broken away to better illustrate the construction thereof.

Figure 4 is a sectional view on the line 45 4—4 of Figure 3.

Figure 5 is a perspective view of a short section of the binding material which this device is adapted to apply to the edge of a panel.

Figure 6 is a top plan view of a somewhat

modified form of the device of the invention showing a strip cutting device and a stapling device applied thereto.

Figure 7 is an elevational view of the modified form of the device illustrated in Figure 6.

Referring to the drawings in detail, Figure 1 illustrates the application of the device of the invention. In this figure, the numeral 10 generally indicates a panel such as a 60 glass window panel for a vehicle body. The numeral 12 generally indicates a strip of binding material usually formed of rubber, which is applied to the edge of the glass panel to form a protective covering for the 65 sharp, rough edges of the panel, and also to provide a weatherbead for the panel when the panel is mounted in a vehicle body to prevent water from passing into the body between the panel and its support. 70

The form of this rubber binding is particularly illustrated in Figure 5, and comprises a channel shaped member having a web portion 13 and two flange portions 14 and 15 enclosing a slot which is adapted 75 to receive the edge of the glass panel. It will be noted that the free edges of the flange portions 14 and 15 are closer together than the portions of the flanges which are attached to the web 13, thus making it necessary to spread the flange portions apart before the strip can be pressed upon the panel. This operation has formerly been done entirely by hand, the panel 10 being placed upon a bench "B" and inserted in the guide 80 "G". The flange members were then separated by the forefingers of the operator and the binding forced upon the edge of the panel with the thumbs. As the binding was placed upon the panel, it was stretched by 85 the operator and the panel turned to different positions until the binding had been placed entirely around it. The over-lapping portion of the binding was then cut off and a staple driven into the binding to hold the 90 ends together.

That part of the operation which comprises inserting the binding upon the edge of the panel was found to be slow and tedious 100 and also a fruitful source of minor injuries.

as the hand of the operator frequently came accidentally into contact with the rough, sharp edges of the panel resulting in many minor cuts and abrasions. While these injuries were not generally of a serious character, and if properly treated were not particularly dangerous, they would cause the operators on this particular operation to lose a considerable amount of time, thereby rendering the operation more expensive than it should be, as well as causing a considerable amount of discomfort to the operators. The device which forms the subject matter of this invention was designed to obviate this condition.

Referring to Figure 2, the numeral 18 indicates a tubular handle portion formed of sheet metal. This handle portion is provided along one side thereof with a guard member 19, the form of which is illustrated in section in Figure 4.

From an inspection of Figure 4, it will be seen that the guard member comprises a rolled upper portion 20, and a straight depending portion 21 having a small bead 22 formed upon the lower end thereof. This guard member 19 may be formed integrally with the handle portion 18 or may be formed separately and secured thereto by any suitable means such as welding, soldering, or by rivets or screws.

Within the tubular handle 18, there is a spreader member 24 secured to the bottom portion of the handle by means of the screws 25. Referring to Figure 3, it will be observed that this spreader member 24 comprises a straight shank or securing portion 27 provided with screw threaded apertures for the screws 25, and an upturned, wedge shaped, portion 28 which projects upwardly into the tubular handle portion and is designed to pass between the flange portions 14 and 15 of the binding strip 12 to separate these flange portions as particularly illustrated in Figure 4.

From an inspection of Figure 2, it will be observed that forwardly of the inner edge of the upturned portion 28 of the member 24, the bottom portion of the tubular handle member 18 is cut away leaving a pair of spaced side members 30 and 31 in the forward end of which a roller member 33 is mounted upon a shaft 34 which projects through suitable apertures in the side members 30 and 31. Beyond the apertures the side members 30 and 31 are bent backwardly upon themselves and are then flared out so that the side member 30 forms a finger rest 35 and the side member 31 forms a thumb rest 36. The backwardly bent portions of the side members 30 and 31 also serve to retain the shaft 34 in the apertures provided for it in the side members. Washer members 38 and 39 are placed between the ends of the roller and the side members 30 and 31.

From a further inspection of Figure 2, it will also be observed that the end of the tubular handle portion 18 opposite the roller 33 is flared out at 40 and that the portion of the handle member surrounding the spreader 24 is bulged out at 41 to allow a sufficient opening in the top of the handle member to start the binding strip over the spreader 24 and under the roller 33.

The operation of the device is as follows:

The rubber binding strip 12 is threaded through the tubular handle 18 as illustrated in Figure 3, the upturned portion 28 of the spreader 24 being inserted in the slot 16 of the binding strip and the binding strip then being carried under the roller 33. This operation applies the tool to the binding strip. The end of the strip projecting forwardly beyond the roller 33 is then inserted upon the panel as illustrated in Figure 1. The tool is then drawn around the edge of the panel, the spreader 24 separating the flanges 14 and 15 so that they pass easily over the edges of the glass and the roller 33 forcing the binding strip firmly down upon the panel.

After a certain amount of the strip has been applied to the panel, the tool is moved away from the panel and the operator grasps the binding strip immediately in front of the tool with his right hand, at the same time holding the opposite end of the strip upon the panel with his left hand, and stretches the binding strip upon the panel. When the binding strip has been applied entirely around the panel, the over-lapping end of the strip is cut off and the two ends of the strip are forced flush together. A metal staple is then driven through the strip straddling the cut to hold the ends of the strip together and thereby form a continuous binding upon the panel.

In the form of the invention illustrated in Figures 6 and 7, the guard member 19' is made somewhat shorter than the guard 19 illustrated in Figures 1 to 4 inclusive. Otherwise the tool is substantially the same as that illustrated in Figures 1 to 4, and has secured thereto by suitable means such as the screws 45, a strip cutting device generally indicated at 46, and by means of the screws 47 a stapling device generally indicated by the numeral 48. Referring particularly to Figure 7, the strip cutting device comprises a bracket 50 having secured to one edge thereof a slide 51, and a stem 52 having at the upper end thereof a knob 53 is mounted upon the slide 51 and carries at the lower end thereof a clamp 54 in which is secured the upper portion of a knife blade 55. The stem 52 is urged upwardly by means of a compression spring, not illustrated, to normally retain the knife blade 55 above the binding strip 12. Pressure on the knob 53 however, will force the stem 52 down upon the guide 51 and will force the knife blade 54 through the binding strip 12.

to cut the binding strip to the proper length.

The stapling device 48 is mounted upon the side of the tool and comprises a bracket member 60 supporting a guide 61 which in turn supports a stem 62 upon which is a knob 63. Below the bracket 60 is a staple magazine 65 which holds a clip of staples which are spring pressed upwardly for the stapling device. The stem 62 is normally urged away from the tool by means of a compression spring or other suitable device but pressure upon the knob 63 will force the stem 62 toward the tool and cause a staple to be inserted into the adjacent ends of the binding strip. As the specific structure of a stapling device of this character is old and well known, it is believed that a further description is unnecessary for the purpose of this disclosure.

In the operation of the modified form of the device, the binding strip is applied to the panel as described above. When the strip has been applied entirely around the panel, the rear end portion of the tool is raised, the knob 53 is depressed to cut off the raised up end of the binding strip. The two ends of the binding strip are then forced directly together and the knob 63 is depressed to secure the ends together by means of a metal staple.

Having now fully described the construction and operation of the device of my invention so that others skilled in the art may clearly understand the same, what I claim as new and desire to secure by Letters Patent is as follows:

35 What I claim is:

1. A tool for applying a rubber binding to a glass panel comprising, a handle portion, a roller for pressing the binding upon the panel, and a spreader secured to the handle and disposed between the handle and the roller for spreading the binding as it is applied to the panel.

2. A tool for applying a rubber binding to a glass panel comprising, a tubular handle portion having parallel extensions at one end thereof, a roller mounted between said extension for pressing the binding upon the panel, and a spreader secured to the handle and disposed between the handle and the roller, whereby the tubular handle is disposed in advance of the roller during operation of the device and serves as a guide for said binding.

3. A tool for applying a rubber binding to a glass panel comprising, a hollow handle portion having a pair of parallel extensions upon one end thereof formed of sheet metal, a roller mounted between said extensions, the ends of the extension being bent backwardly and outwardly to retain the roller in place and form finger rests on the handle, a spreader secured to the handle and disposed between the handle and the roller, and a sheet metal guard secured to one side of said handle.

4. A tool for applying a rubber binding strip to a glass panel comprising, a tubular

handle portion formed as a guide for said binding strip, a roller on said handle for forcing the binding strip upon the panel, and a spreader within said handle portion for spreading the binding strip as it is applied to the panel.

5. A tool for applying a rubber binding to a glass panel comprising, a tubular handle portion through which the binding is guided, a roller on said handle portion for forcing the binding upon the panel, and a guard upon said handle to protect the hand of the operator from the edge of the glass panel.

6. A tool for applying a rubber binding strip to a glass panel comprising, a tubular handle portion, means on said handle portion for forcing said binding strip onto said panel, a guard on said handle portion for protecting the hand of the user from the edge of the panel, and a finger rest on said handle portion adjacent to said roller.

7. A tool for applying a rubber binding strip to a glass panel comprising, a tubular handle portion, a roller on said handle portion for forcing said binding strip onto said panel, a finger rest on one side of said roller, a thumb rest on the other side of said roller, said finger rest and thumb rest constituting a guiding means for said tool.

8. A tool for applying a binding strip to a panel comprising, a tubular handle portion, means in said handle portion for spreading said binding strip and forcing it over the edge of said panel, and means mounted on said handle for cutting off said binding strip.

9. A tool for applying a binding strip to a panel comprising, a tubular handle portion, means in said handle portion for spreading said binding strip and forcing it over the edge of said panel, and means mounted on said handle for stapling together the adjacent ends of said binding strip.

10. A tool for applying a binding strip to a panel comprising a tubular handle portion, means in said handle portion for spreading said binding strip and forcing it over the edge of said panel, means mounted on said handle for cutting off said binding strip, and means also mounted on said handle for stapling together the adjacent ends of said binding strip.

Signed by me at South Bend, Indiana, this 15th day of September, 1931.

FREDERICK HENRY.
